UNITED STATES PATENT OFFICE

CHARLES J. ELLIS, OF CINCINNATI, OHIO, ASSIGNOR TO THE CINCINNATI CAR CORPORATION, OF CINCINNATI, OHIO, A CORPORATION OF OHIO

CONVERTIBLE SIDE-DOOR OPENING FOR RAILWAY CARS

Application filed February 1, 1929. Serial No. 336,814.

This invention relates to convertible side door openings for street cars, and more particularly to exit doors.

The object of this invention is to provide a doorway that may be converted from a single doorway to a double doorway, or from a double to a single doorway. It is particularly the object of this invention to convert a doorway of a two-man car into an exit doorway for a one-man car, or back from a one-man car to a two-man car.

A further object of this invention is particularly to construct a variable doorway used in connection with sliding doors adapted 15 to close both a normal doorway, and one that has been enlarged.

A further object of this invention is to provide a doorway of this kind which is limited or restricted by placing a panel or sash 20 within the doorway so that the doorway is restricted; it is also an object of this invention to provide a slidable door and a nesting means for said door which may be operated both to close the full doorway or the restrict- 25 ed doorway formed from the full doorway.

While it is particularly the object of this invention to provide in connection with a variable doorway, a slidable door that is adapted to close doorways of this kind, yet 30 it is not the purpose of applicant in applying this invention to use to be restricted to the use of slidable doors alone. For the purpose of illustration, there is shown the accompanying drawings, a preferred embodiment of this invention.

Referring to the drawings:

Figure 1 shows a sectional plan view of the rear end of a street car with a removable panel attached to the exit door thereof.

40 Figure 2 is a vertical section of that part of the side of the car to which the removed panel is attached.

Figure 3 is a side view of the lower part of the panel and the step to which the panel is attached.

45 Figure 4 is a section through the post and part of the panel showing the means by which the post is attached to the panel.

The numeral 1 is used to designate the rear 50 end of the car as a whole, which, as shown

in Figure 1, has the two usual doorways and doors found in cars of this type.

Usually the exit doorways of street cars are double in their nature, one part being used for the entrance of passengers, while the other part is used for the exit of passengers. The full door space in this instance is controlled by one single door, and operated by a single means, and this is the form of car which is generally used when the car is operated by two persons, but in the event it is necessary that the car be used for operation by one person, it becomes necessary to restrict the doorway so as to provide merely for the exit of passengers. To accomplish this adjustment in the size of the doorway, a panel is inserted in one side of the doorway, thereby restricting and varying the size of the doorway.

The doorway as a whole is indicated by the numeral 2, while the removable panel is indicated by the numeral 4, the numeral 3 being used to designate the usual hand rail found in cars where there are entrances and exits at the same doorway.

75 The removable post forming part of the removable panel is indicated by the numeral 5. This post is attached to the panel part by means of screws indicated by the numeral 6, and fully illustrated in Figure 4. The point at which the panel is attached to the permanent side of the doorway of the car is indicated by the numeral 7. The means of attachment is the same as that found between the door post and the adjacent and cooperat- 80 ing part of the door for the doorway. How- 85 ever, any suitable modification might be used to make the connection between the panel and the post secure during the time the panel is used. The lower parts of the panel and posts are attached to the step 8 of the car or to the platform floor if folding steps are used, by means of an angle iron indicated by the nu- 90 meral 9, and bolts 10, passing through the one part of the angle iron and steps, and the other part of the angle iron and panel and post.

95 On the body of the car, just above the pas- 100 sage way, there is a ledge indicated by the numeral 11, which is adapted to support and

carry the structure supporting the upper end of the panel, and providing a track way for the slideable door when closing this enlarged part of the doorway. Supported 5 immediately above the ledge member 11, is a metal strip indicated by the numeral 12, which has its lower edge bent up to form a track way 13 which is engaged by a supporting bracket 14 attached to the upper end of 10 the panel and post. In order to support the upper end of the panel, the bracket member 14 is engaged over the upper part of the runway 13, and fits within the groove formed by the run way and the body of metal strip. 15 In order also to more securely support the upper end of the door, a beam indicated by the numeral 15, extends across the upper end of the panel and rests upon the ledge 11 so that added support is given the upper end 20 of the panel.

This structural relation between the panel and the parts of the car engaged thereby is such that the panel is held firmly attached to the car, but may be easily removed by merely 25 taking the bolts 10 out of the steps or platform floor of the car, and swinging the lower end of the panel inward so that the parts 13 and 14 may be disengaged. For the purpose of permitting this swinging movement of the 30 panel, there is provided a space between the extreme upper part of the panel, and the body of the car, as is shown in Figure 2. The panel may be constructed in any suitable manner; it may be wholly of wood, or the 35 lower part may be wood and the upper part glass, as is usually the case in panels of this kind, or metal with or without glass.

For the purpose of closing the doorway when in its restricted or its enlarged condition, there are provided door sections which 40 as a whole are indicated by the numeral 16, and the sections, or panels, of the door are indicated by the letters *a*, *b*, and *c*. Each panel of the door is connected to another 45 panel by means of some hinge structure 17 that permits a slight swinging movement between the sections of the door, so the door may conform itself to the part of the car to be engaged thereby, when in closed position.

50 For the purpose of receiving the door when not in use and when the doorway is open, there is provided a pocket in the side of the car adjacent the door, into which the door is moved for the purpose of opening 55 the doorway. This pocket is indicated by the numeral 18, as is clearly shown in Figure 1.

The door may be shifted from a closed to 60 an open position, or from the open to a closed position by means of a door motor usually found in cars of this type, and used for this purpose. The motor is adapted to operate the door for both its limited and its full movement. This is accomplished by means of 65 certain adjustment so that the extent of the

movement of the motor is regulated so that it is adjusted to the extent of the movement of the door, for the purpose of closing and opening the passage way into the car whether the panel is in place in the doorway or is removed. 70

I desire to comprehend within my invention such modifications as may be clearly embraced within my claims and the scope of my invention. 75

Having thus fully described my invention, what I claim is new and desire to secure by Letters Patent, is:

1. In a railway car having a doorway, a panel adapted to be placed in said doorway 80 to restrict it, and means for removably attaching said panel to the car to restrict said doorway.

2. In a railway car having a door receiving pocket and a full doorway, a panel in said doorway to restrict said full doorway to a normal doorway, and a door adapted to close either of said doorways. 85

3. In a railway car having a doorway, a panel adapted to be attached to said car to 90 restrict the doorway, and a door slidably supported by said car and adapted to close said doorway whether restricted or unrestricted.

4. In a railway car having a doorway, a 95 panel adapted to be attached to said car to restrict the doorway, and a door supported by said car and adapted to close said doorway whether restricted or unrestricted.

5. In a railway car having a doorway, a 100 panel adapted to be placed in said doorway to restrict it, hook means to support one end of the panel by the car, and additional means to support the other end of the panel by the car. 105

6. In a railway car having a doorway and a step, a panel adapted to be placed in said doorway to restrict it, and means for removably attaching said panel to the step of the car.

7. In a railway car having a doorway and a step, a panel adapted to be placed in said doorway to restrict it, means for suspending the panel on the car, and means for removably attaching one end of said panel to the 115 car step.

8. In a railway car having a doorway and step, a panel adapted to be attached to the car and detachably supported by said step to restrict the doorway, and a door adapted to close said doorway, restricted or unrestricted. 120

9. In a railway car having a variable doorway and a pocket, a door adapted to close said doorway in any of its conditions of variation when in a closed or partially closed position and be housed in said pocket when in another position. 125

10. In a railway car having a doorway and a pocket, a panel adapted to fit within said doorway to vary the size thereof, and a door 130

adapted to close said doorway in its restricted or in its unrestricted condition, and adapted to be housed within said pocket for the purpose of opening the doorway.

5 11. The combination with a railway car having a doorway and a pocket therein, of a panel attached at each end to said car in said doorway to restrict it, and door means to close said doorway with or without said panel and adapted to be received into said pocket when the doorway is open.

In testimony whereof, I affix my signature.
CHARLES J. ELLIS.
